UNITED STATES PATENT OFFICE.

JOHN K. SHAW, OF MINNEAPOLIS, MINNESOTA.

REDWOOD-BARK WALL BOARD.

Application filed October 23, 1920. Serial No. 419,048.

To all whom it may concern:

Be it known that I, JOHN K. SHAW, a citizen of the United States, residing at Minneapolis, in the county of Hennepin and State of Minnesota, have invented certain new and useful Improvements in Redwood-Bark Wall Board; and I do hereby declare the following to be a full, clear, and exact description of the invention, such as will enable others skilled in the art to which it appertains to make and use the same.

This invention relates to a wall fibre board composed of the fibrous bark material obtained from the well known redwood trees growing in California, and elsewhere, and has for its object to provide a heat insulating board which will be more efficient in use and less expensive to produce than those heretofore proposed.

With these and other objects in view the invention consists in the novel features and combinations of features constituting the wall board, all as will be more fully herein-after disclosed and particularly pointed out in the claims.

In order that the exact invention may be the more clearly understood, reference is had to the accompanying drawings forming a part of this specification in which like numerals designate like parts in all the views:—

Figure 1 is a diagrammatic sectional view of an apparatus suitable for making a board in accordance with this invention;

Figure 2 is a diagrammatic view illustrating the flow of fibres and water to a foraminous traveling surface;

Figure 3 is a view similar to Figure 2 illustrating how the fibres are entangled with each other;

Figure 4 is a diagrammatic view of a finished board made in accordance with this invention; and

Figure 5 is a diagrammatic view illustrating a bundle of the red wood bark fibres detached.

In preparing the fibres from which to make the above board I proceed as follows:—The redwood bark is first chopped or otherwise removed from the tree, and is broken up into suitable sizes whereupon it is partially cooked with a caustic soda or other suitable solution, or until the chips are softened.

After thus softening the chips by the

cooking operation they are reduced by suitable apparatus to the form of a pulp. For this purpose I can use any well known beating engines and refiners. The pulp will be found to consist of a mixture of relatively long very fine hair like fibres and a powder like substance which originally encased the fibres or bound them together. The pulp material thus formed can be used mixed with this powder, or it can be washed and the fine powder like material thus separated from the hair like fibres.

If the powdered material is separated from the hair like fibres, the latter are passed through a felting machine such as that illustrated in Figure 1, whereupon the fibres are felted together into a compact board, which is passed between rollers. This machine, as illustrated, may consist of any suitable tank 1 for holding the stock containing water and cooked fibres, of a bottom 2, an inclined false bottom 3 located above the bottom 2, a roll or drum 4 near the lower end of said false bottom 3, a plurality of supporting rolls 5, a guide and compression roll 6 adjustable on the slide 7, a guide roll 8 similar to the roll 4, and a guide and tensioning roll 9 adjustable on the means 10. Passing over the rolls just mentioned is the endless foraminous belt or surface 11, conveniently made of wire cloth and having the oppositely moving portions or runs 12 and 13. Between the runs 12 and 13 is located the water outlet 15 provided with the controlling means or gate 16 which may be suitably manipulated as by the handle or other device 17.

Coacting with the foraminous surface or belt 11 and in close proximity thereto, as regards one portion thereof, is the foraminous belt 18 passing over and around the series of guide rolls 19, 20, 21, 22, 23, and 24. Said belt 18 also passes over the compression guide rolls 25 coacting with the compression roll 6 and adjustably mounted on a movable means 26. 27 represents a tension and guide roll, adjustably mounted on the means 28, and 29 an outlet for the water passing through the belt 18 controlled by the gate 30 and adjustable through the handle 31. 32 and 33 represent suitable water seals of flexible materials for the belts 11 and 18 respectively. 35 represents a channel or passage for water and fibres which may be maintained at any desired hydrostatic head 36, 37 an opening from the channel 35 into 110

the tank space or chamber 38, and 39 a partition separating said chamber or space 38 from the remainder of the tank.

40 represents a second channel for water and pulp fibers, 41 the head thereof, 42 an opening from said channel into the tank chamber or space 43, and 44 a partition which with the partition 39 serves to separate said space 43 from the rest of the tank.

10 45 represents a third channel for water and fibers having a head 46, 47 an opening into the tank chamber or space 48 and 49 a partition coacting with the partition 44 to segregate said space 48 from the remainder 15 of the tank.

15 The foregoing mechanism is, or may be substantially the same as that disclosed in my copending application #368995, filed March 26, 1920, and entitled fibre boards of 20 felted interlaced fibers.

20 In felting redwood fibers according to this invention, it is preferred to use long fibers, but of course, the fibers may be broken up in the beating engine, and those of 25 any usual length may be employed. By reason, however, of the direction of flow of the water through the chambers 38, 43, and 48, and by reason of the natural tendency of the flow of water to laterally separate said 30 fibers, the latter will be brought into positions more or less parallel to each other, and more or less perpendicular to the line of travel of the surface 18 while at the same time all of said fibers and bundles of fibers 35 will occupy positions more or less staggered with relation to their neighbors, as shown.

Accordingly, a large percentage of the forward ends 61 of said fibers and bundles of fibers will first contact with said surface 46 13, and will be carried along by the belt from the positions shown in Figure 2, to those shown in Figure 3, for the rear ends 62 of said fibers and bundles of fibers will have lagged behind the front ends 61 in the 50 water, so in the front row, said fibers assume a somewhat curved or bent shape.

The second row or those fibers 63 immediately following and which have not reached the surface 13 but have reached the 55 rear ends 63 of the fibers 60 are now forced by the oncoming water to contact at their forward ends against the curved fibers 60. As said fibers 63, originally, due to their parallel positions as shown at 63 in Figure 2 were more or less staggered or interlaced with the fibers 60 before the whole became curved, it is evident that this interlacing or entangling action between the fibers 60 and 63 will be enhanced or increased by the oncoming water after said curvature takes 60 place. It results from the actions just described that said fibers 63 become themselves more or less curved as indicated in Figure 3, and that a third row of fibers 64 65 which are also interlaced or staggered with

the fibers 63 will become in time curved and entangled with the fibers 60 and 63, that have preceded said fibers 64.

It thus results that owing to the floating of the fibers into parallel interlaced, or staggered positions, and in a direction transverse to the traveling surface 13, the entanglement of the fibers is continuous between successive rows and the pressure of the water causes the whole to be very thickly 70 assembled in their interlaced positions on said surface, thus forming an open mass of fibers more compact next to the wire than away from it. This mass is carried through the opening 70 into the space 43 with one 75 or more partially curved and partially entangled layers similar to the fibers 60 and 63 clinging to it. In said chamber or space 43 other fibers similar to the fibers 64 become interlaced and entangled with the layers on the belt, and the process of entanglement and massing proceeds as before.

In the meantime, layers of fibers in all respects similar to the layers 63, 64 and 60 are interlaced, entangled and massed on the 80 traveling belt 18 from the space or chamber 48. This second massing of fibers is carried through the opening 71 by the belt 18 in a condition similar to the first mentioned mass that passes the opening 70, and the fibers in 85 the space 43 interlace and become entangled with said second mass in a manner similar to that described in connection with said first named mass.

The result is, owing to this parallel and 90 staggered relation illustrated, the fibers in the space 43 constitute a third mass of fibers which are interlaced and entangled with each other, as well as with each of said first named masses. As a result of the foregoing 95 entanglement, of the various fibers and the motion of the surfaces 13 and 18, the mass of fibers are carried through the openings 75 between the compression or compacting rolls 6 and 25 and is formed into a sheet or board 100 110 115 120 125 130 135 140 145 150 155 160 165 170 175 180 185 190 195 200 205 210 215 220 225 230 235 240 245 250 255 260 265 270 fibres may be placed in the chamber 40. In such cases the layers 77 and 75 will be correspondingly different. On the other hand, if it be desired to make a board of uniform fibres throughout, of course, the chambers 45 and 40 and 35 will contain a uniform mixture of fibres. A most excellent board is made by so beating one portion of the redwood bark fibres as to finely disintegrate the bundles of fibres and to so beat another portion of said bark as to leave the ultimate fibres in the form of bundles of fibres of a greater or less size, and to mix these said very fine fibres with these said bundles of fibres and felt the whole into a coherent entangled mass. In such case, the larger bundles of fibres provide air cells and the finer ultimate fibres securely tie the bundles together, thus making a board which 20 trains an unusually large quantity of air and which therefore has a very high heat insulating power, while the board itself owing to the exceptional resiliency, strength, pliability and strength of these redwood fibres is exceedingly flexible, pliable, resili- 25 ent and strong.

The exceptional character of redwood fibres for making wall boards may be gathered from Figure 5, wherein the entire bundle of fibres is lettered 60, and the very fine hair like ultimate fibres are lettered 100 and 101.

The pressure used in forming the board 29 will depend upon the qualities desired in the finished product. If it is desired to provide a high heat insulating quality to the board, the pressure is slight, so that a large quantity of air will be entrained in the interstices of the board, while if the board is 35 desired to take on more the qualities of lumber and to have a harder finish, the pressure is increased which greatly increases the density of the board, and the latter may then be substituted for lumber in many uses.

An important feature of this invention resides in the discovery that the individual fibres are associated with a substance the chemical composition of which I do not know, but which renders them non-inflammable. That is to say, a board made as above described may be ignited by a flame but it will not continue to burn if left alone. Therefore, by employing this redwood bark material for the making of fibrous boards, of this character, I do not have to fireproof the material as has been the case heretofore.

Should the above mentioned powder like substance be left with the hair like fibres or bundles of fibres, the whole mixture of pulp 60 is subjected to the action of the felting machine, and the massed fibres are passed through the rollers and after having been treated as above disclosed, whereupon the board will be found to be with the same

pressure as heretofore more dense and more 65 rigid and more nearly resembling artificial lumber. Further, of course, a greater weight of board is produced from a given weight of bark, when said powdered material is left in the pulp than when it is removed. 70

The ultimate redwood fibres being unusually long and pliable, they can with ease be mixed with other shorter fibres, filling material or various well known waste materials, and thus produce excellent substitutes for lumber when subjected to sufficient pressures. 75

It will be obvious that those skilled in the art may vary the details of the invention without departing from the spirit 80 thereof, and therefore, I do not wish to be limited to the above disclosure except as may be required by the claims.

What I claim is:

1. The herein described wall fibre board 85 composed of different layers one of said layers consisting of the fibres of redwood bark and one of said layers consisting of other vegetable fibres and the fibres of all of said layers interlaced with each other, 90 substantially as described.

2. The herein described fibre board composed of different layers one of which is composed of redwood bark and one of which is composed of another vegetable fiber, said 95 layers interlaced with each other, and the fibres of the redwood bark carrying there- with their natural non-inflammable substances, substantially as described.

3. The herein described heat insulating 100 fibre board containing bundles of fibres from red wood bark of different sizes bound together by smaller fibres and also containing bagasse fibers and all of said fibres being substantially non-inflammable, sub- 105 stantially as described.

4. The herein described wall board containing a substantial percentage of fibres from redwood bark and from bagasse, said board provided with different layers of interlaced fibres and all of said fibres being compressed together to form a board of pronounced resiliency and tensile strength, substantially as described. 110

5. The herein described new fibre board 115 containing a substantial percentage of red- wood bark mixed with a powder like ma- terial obtained from the chemical treat- ment of said fibres, substantially as de- scribed. 120

6. The herein described fibre board comprising different sized bundles of fibres from redwood bark mixed with a binding ma- terial obtained from the chemical treat- ment of said bark, substantially as de- 125 scribed.

In testimony whereof I affix my signature.
JOHN K. SHAW.
